UNITED STATES PATENT OFFICE.

MICHAEL MYSЛИWICZ, OF WEHRUM, PENNSYLVANIA.

COAL-CUTTING MACHINE.

1,116,907.

Specification of Letters Patent.

Patented Nov. 10, 1914.

Application filed March 6, 1913. Serial No. 752,350.

To all whom it may concern:

Be it known that I, MICHAEL MYSЛИWICZ, a subject of Emperor of Austria-Hungary, residing at Wehrum, in the county of Indiana and State of Pennsylvania, have invented certain new and useful Improvements in Coal-Cutting Machines, of which the following is a specification, reference being had therein to the accompanying drawings.

This invention relates to a coal mining machine, and the primary object of my invention is to provide a hand operated machine wherein simple and effective means are employed, as hereinafter set forth for imparting an oscillatory movement to a plurality of mining bits, whereby a horizontal kerf can be economically and expeditiously produced but permits of coal being broken down and easily mined.

A further object of this invention is to provide a machine of the above type that can be easily, quickly and advantageously used for performing such work as ordinarily is accomplished by the use of a pick, namely, that of providing a kerf or slot whereby a body can descend by gravity or be shattered by resorting to the use of an explosive.

A still further object of this invention is to provide a hand operated cutting machine that can be used in coal mines, quarries or other subterranean passages to facilitate the mining and removing of products, and to this end, the machine has been constructed upon compact and durable lines that permit of its use in a comparatively small space.

With the above and other objects in view, the invention resides in a novel construction, combination and arrangement of parts to be hereinafter specifically described and then claimed.

Reference will now be had to the drawing, wherein:

Figure 1 is a plan of the machine in a horizontal position, with parts broken away. Fig. 2 is a side elevation of the machine with the breast piece removed, and parts broken away. Fig. 3 is an enlarged cross sectional view of a portion of the machine. Fig. 4 is a horizontal sectional view taken on the line IV—IV of Fig. 3. Fig. 5 is a similar view taken on the line V—V of Fig. 3. Fig. 6 is an enlarged perspective view of a portion of a lever with a scraper adapted to form part of the machine. Fig. 7 is a detail view in cross section illustrating the swiveled

connection between the housing and the breast bar.

A cutting machine in accordance with this invention comprises two parallel semi-circular frames 1 having the ends connected by an integral cross-bar 2 and this bar, intermediate the ends thereof is provided with a slot 3, the purpose of which will presently appear. The bar 2, at the ends thereof, is slotted, as at 4 and pivotally mounted in said slots by transverse pins 5 are the ends of hand operating links 6. These links are flat and the outer ends of said links are provided with hand grips 7.

The upper side of each link is provided with transverse equally spaced pivoted scrapers 8 that are hinged, as at 9 to the links. The scrapers 8 are adapted to lie flat against the link as the link moves into a kerf, but as the link is pulled out of the kerf, the scrapers 8 assume a position at right angles to said links, whereby they can remove coal or other matter from a kerf produced by the machine. To maintain the scrapers 8 at right angles to the link 6, said link is provided with depending parallel pins 10, and these pins brace the scrapers while the same are impinging and removing coal from a kerf.

Arranged upon the outer sides of the frames 1 are a plurality of equally spaced cutting bits 11, said bits having reduced ends 12 mounted in sockets 13 provided therefor in the frames 1. This construction is best shown in Fig. 3. The inner side of one of the frames 1 is provided with a plurality of equally spaced inwardly projecting pins 14, and these pins are adapted to engage a pin wheel 15 that is mounted upon the shank 16 of an auger 17^a. The shank 16 of the auger 17^a is rotatably mounted in a cylindrical head 17, and this head is provided with circumferentially arranged ratchet teeth 18 adapted to be engaged by a resilient pawl 19 carried by the lower side of the pin wheel 15. The shank 16 is provided with a flange 16^a which constitutes a support for the head 17. The head 17 is fixedly secured to the shank 16 whereby the head 17 and shank 16 will turn together.

The cylindrical head 17 has oppositely disposed arms 20 and said arms are fixedly connected, as at 21 to a rectangular housing 22, carried by the outer end of a breast bar 23. The housing 22 is swivelly connected to the breast bar 23 and as said housing 22

is fixed to the head 17, the said housing and head swivel together upon the breast bar, and as the shank 16 is connected to the head 17, it is obvious that said shank, head and 5 housing turn together. The breast bar 23 extends through the slot 3 of the bar 2 and is pivotally mounted within said slot by a transverse screw or pivot 24. The breast bar 23 has an adjustable telescopic sleeve 10 23^a provided with a pivoted breast piece 23^b.

To place the cutting machine in operation, it is only necessary to rotate the auger 17^a sufficiently for the same to engage in a body 15 of coal and support the frame 1 relatively to the body of coal. The placing of the auger 17^a in engagement with the body of coal can be accomplished through the medium of the breast bar 23. By then gripping the links 6, the frames 1 can be oscillated 20 relatively to the breast bar 23. A movement of the frames 1 in one direction imparts a partial rotation to the pin wheel 15 and thereby further anchors the auger 17^a in the body of coal. A movement of the 25 frames 1 in an opposite direction allows the resilient pawl 19 to recede over the ratchet teeth 18 of the head 17. The bits 11 engage the body of coal and produce a semi-circular kerf, as shown in Fig. 1, and as the links 6 30 move into the kerf, the scrapers 8 are carried therein to assume an upright position as the levers are drawn out of the kerf, consequently coal is removed from the kerf and the operation of the machine not interfered 35 with until a kerf, within the scope of the machine has been cut.

By arranging one-half of the cutting bits 11, in an opposite direction from the other half, a quadrant of the kerf is cut at each 40 oscillation of the frames 1, and each alternate operation of said frames feeds the machine farther into a kerf or body of coal, thus permitting of a body of coal being undermined in a small space where a pick or 45 other implement could not be easily manipulated.

The machine in its entirety is constructed of soft and durable metal, and while in the drawing, there is illustrated a preferred embodiment of the invention, it is to be understood that the structural elements are susceptible to such variations and modifications 50

as fall within the scope of the appended claims.

What I claim is:—

1. A cutting machine including parallel semi circular frames, a bar connected to said frames, a handle bar pivotally connected to said bar, an auger loosely supported by said handle bar and adapted to have movement imparted thereto by an oscillatory movement of said frames, and links connected to the bar of said frames to facilitate an oscillatory movement to said frames. 55

2. A cutting machine comprising parallel semi circular frames, a bar connected to said frames, a handle bar pivotally connected to said bar, an auger loosely supported by said handle bar and adapted to have movement imparted thereto by an oscillatory movement 60 of said frames, links connected to the bar of said frames to facilitate an oscillatory movement to said frames, a plurality of bits carried by said frames, and hinged scrapers carried by said links. 70

3. A cutting machine including semi circular frames, a bar connecting said frames, cutting bits carried by said frames, links pivotally connected to said bar to facilitate imparting an oscillatory movement to said frames, scrapers carried by said links, means including an auger for anchoring said frames relatively to a body of coal, and a breast bar carrying said means and having the said bar pivotally connected thereto. 75

4. A kerf-cutting machine comprising parallel semi circular frames, a bar connecting said frames, links connected to said bar for oscillating said frames, bits carried by said frames, a breast bar supported by the bar of said frames, an auger movably supported relatively to said breast bar and adapted to anchor said frames relatively to a body of coal, and means actuated by an oscillatory movement of said frames for feeding said auger into a body of coal whereby a kerf can be produced by oscillating said frames. 90

In testimony whereof I affix my signature in the presence of two witnesses.

MICHAEL MYSIWICZ.
